CLAIM

The ornamental design for gaming headset, as shown and described.

DESCRIPTION

FIG. 1 is a perspective view of a gaming headset in accordance with the present invention, the front face of the ear cup is a mirror image;

FIG. 2 is a back view of the embodiment of the gaming headset shown in FIG. 1;

FIG. 3 is a bottom view of the embodiment of the gaming headset shown in FIG. 1;

FIG. 4 is a front view of the embodiment of gaming headset shown in FIG. 1;

FIG. 5 is a left side view of the embodiment of the gaming headset shown in FIG. 1;

FIG. 6 is a right side view of the embodiment of the gaming headset shown in FIG. 1; and,

FIG. 7 is a top view of the embodiment of the gaming headset shown in FIG. 1.

The broken lines showing the environment in the FIGURES are for illustrative purposes only and form no part of the claimed design.

1 Claim, 7 Drawing Sheets
